OXYGEN LANCING OF FURNACE FLUES
AND CHECKERSThomas A. Thompson, Toronto, Ohio, assignor
to National Steel Corporation, a corporation
of Delaware

Application July 17, 1950, Serial No. 174,259

8 Claims. (Cl. 263—52)

1

This invention relates to the removal of dust from passages, the dust having previously been deposited in the passages from gaseous products of combustion flowing therethrough, and more particularly relates to the removal of such dust while at an elevated temperature through the use of oxygen or oxygen rich gas.

In the present type of open hearth furnace, for example, there is a smelting or hearth chamber in which the metal is melted and refined. The furnace installation includes at least one regenerator for each end of the furnace. In some furnaces oil is used for fuel. Usually an oil burner is provided at each end of the furnace. In operation, air is blown through a hot regenerator and the preheated air then passes into one end of the furnace to provide the oxygen to support combustion in the furnace. The incoming air is preheated to an elevated temperature to reduce the quantity of heat which must be supplied by the fuel. The hot gaseous products of combustion produced in the hearth chamber pass out the opposite end of the chamber and then through a second, previously cooled regenerator to heat this second regenerator. The gases from the second regenerator pass through flues to a stack and to the atmosphere. Periodically the direction of gas flow is reversed so that each regenerator alternately is heated by the hot gaseous products of combustion and is then cooled by the counter-currently flowing air. Each regenerator is made up of refractory brickwork arranged so that there is a large number of relatively small passages through the brickwork. This brickwork is commonly referred to as "checkerwork." The gaseous products of combustion are laden with dust. This dust is deposited in the passages leading to, through and from the checkerwork. These deposits of dust build up, and the removal of this dust, particularly from the flue passages, is quite difficult. It is necessary periodically to shut down the furnace and have a crew of workmen clean the dust out of these flues and the checkerwork.

It is an object of the present invention to effect the removal of dust from passages quickly and with a minimum of effort.

Another object of the present invention is to provide an improved method of and apparatus for removing dust that previously has been deposited in a passage from gaseous products of combustion.

Another object of the present invention is to effect the removal of dust deposits from a passage without the necessity of shutting down the apparatus associated with the passage or interrupting the flow of gas through the passage.

2

Another object of the present invention is to provide an improved method of and apparatus for removing dust from passages leading to, through or from regenerators of refractory brick-work.

I have discovered that dust deposited from gaseous products of combustion can be readily and thoroughly removed from a passage, for example, an open hearth flue, by impinging a stream of oxygen or oxygen rich gas against the dust deposit while the dust is at an elevated temperature. I have found that when a stream of oxygen or oxygen rich gas impinges on the hot dust in an open hearth flue, dust glows and apparently deteriorates into a residue of fine particles and gases, which the draft through the flue will carry out of the flue and up the stack. The oxygen converts the relatively heavy dust, which the draft normally will not move, into a residue which the draft will carry out of the flue.

The necessary purity of the oxygen that is used for removing the dust is a function of the temperature of the dust. When the dust is at a temperature of at least 1000° F. or higher, the dust removing gas should contain at least 90% by volume of free oxygen. When the dust is at a higher temperature of at least 1400° F. or higher, a gas that is predominately oxygen may be used. Normally the oxygen rich gas will be composed of oxygen and nitrogen. Any gas may be used which contains the requisite amount of free gaseous oxygen. The portion of the gas which is not oxygen should be an inert gas that will not combine with the oxygen.

These and other objects of the present invention will become more readily apparent from the following description, taken with the accompanying drawings, in which:

Figure 1 is a side view, partially in section, of an open hearth furnace;

Figure 2 is a horizontal sectional view of the furnace of Figure 1 and illustrating one embodiment of the present invention; and

Figure 3 is a fragmentary sectional view of a portion of the apparatus shown in Figure 2, illustrating a different embodiment of the present invention.

Referring to the drawings and more particularly to Figures 1 and 2, the open hearth furnace 10 contains a hearth of smelting chamber 11 in which the metal is heated and refined while supported on the hearth bottom 12. At opposite ends of the furnace there are slag pockets 13 and 14, each of which is in communication with or opens into a respective end of the chamber 11.

The slag pocket 13 is in communication with the checker or regenerator chamber 14 containing refractory checker brick 15. A passage 16 connects slag pocket 13 and the checker work 15. At the opposite end of the furnace the slag pocket 14 opens through a passage 17 into checker chamber 18 containing refractory checker brick 19. The slag pockets 13 and 14 and the regenerators or checker work 15 and 19 are similar. As shown more clearly in Figure 1, at the bottom of the checker work 19 there are four flues 21 which are separated by the spaced apart walls 22 extending between the bottom of the checker work 19 and the base of chamber 18. At the bottom of the checker work 15 there are walls 23 similar to walls 22 which define flues identical with flues 21. The flues of checker chamber 14 open into flue 25 which is, in turn, in communication with stack 26. The flues 21, which are beneath checker work 19, open into flue 27, which in turn opens to the stack 26. The flues 25 and 27 contain dampers 29 and 30. These dampers are shown in the closed position but either damper may be moved to the open position. A motor driven air blower 31 is connected through conduit 32 to flue 25 and is also connected through conduit 33 to flue 27. A damper 35 is provided in flue 32 and a similar damper 36 is provided in flue 33. Alternatively, the draft of the stack may be used without the blower to draw the gases through the apparatus.

Oil burners 37 are provided at each end of the furnace. These burners are of customary construction and are designed to inject an atomized stream of oil into the chamber 11 where the oil burns to heat the chamber and the metal therein. In operation and assuming that dampers 30 and 35 are closed, and the dampers 29 and 36 are open, then air is blown by the blower 31 into flue 27 and through the checker work 19 where the air is heated. The heated air flows through the passage 17, slag pocket 14 and into the furnace to supply the oxygen for effecting combustion of the fuel oil. The hot gaseous products of combustion flow from the chamber 11 through slag pocket 13, passage 16 and then down through regenerator 15. The hot gases heat the regenerator 15 and then flow through flue 25 to the stack 26. When the regenerator 15 becomes sufficiently heated and the regenerator 19 becomes cooled by the relatively cool air, the dampers are reversed so that dampers 30 and 35 are open and dampers 29 and 36 are closed. With this arrangement the air is blown into flue 25 and through the regenerator 15 where the air is heated and then into the chamber 11. The hot gaseous products flow through slag pocket 14, regenerator 19, flues 21 and then flue 27 to stack 26. Thus, each regenerator is alternately heated and cooled by the countercurrently flowing hot gaseous products of combustion and relatively cool air.

As described so far in detail, the open hearth furnace is of customary construction and may be of any type customarily used in the steel industry. Where gas is used as the fuel, then two regenerators may be installed at each end of the furnace so that one of each pair of regenerators can be used for heating the air and the fuel gas, respectively.

The open hearth furnace as described so far in detail, constitutes no part of the present invention, and the present invention is not limited to the exact details of open hearth structure shown in the drawing. It is to be noted that the walls of the passages are lined with refractory

material and that this lining is at an elevated temperature when the furnace is in operation.

The hot gaseous products of combustion which pass from the smelting chamber through the slag pocket and one of the regenerators and then through the flues to the stack is laden with or contains suspended dust particles. These dust particles collect in the passages, particularly in the passages of the checker work and on the bottoms of the flues. These dust deposits restrict the size of the passages and it is necessary at intervals to clean the checker work and the flues to remove the dust. Attempts have been made to use air or steam to blow the dust out of the passages without success. This dust has a high specific gravity and while the dust can be cleaned off of the checker brick by means of a high velocity air or steam jet, the dust merely falls down to the bottom of the flues so that the dust in the checker work is shifted to the flues. The dust has been found to collect in the flues to a depth of, for example, 20 inches. Attempts to clean the flue passages with air or steam have not been satisfactory. Accordingly it is necessary to periodically shut down the furnace and allow the furnace to cool down sufficiently to enable a crew of workmen to manually scrape the dust out of the flue passages. This is a time consuming operation and is relatively costly.

A sample of flue dust collected from the flues of an open hearth furnace was found to have the following analysis:

	Per cent
Iron	28.37
Carbon	3.17
Manganese	.33
Sulphur	6.51
Silicon	1.55
Alumina	.56
Lime	1.51
Magnesia	.47
Tin	.25
Copper	.30
Nickel	.07
Lead	5.98
Zinc	25.25

The composition of the dust will vary depending on the fuel used and the metal in the hearth, particularly the composition and type of scrap metal used. The high zinc content of this dust resulted from zinc volatilized in the hearth.

In accordance with the present invention, this flue dust is quickly removed when the dust and flue walls are at an elevated temperature and it is not necessary to shut down the furnace to remove the dust. Open hearth flues and passages are provided with suitable openings to permit access to the interior. These openings normally are closed by doors or covers. As shown more clearly in Figure 2, the side wall of flue 27 is provided with an opening 40 normally closed by a door or cover 41. A similar opening 42 is provided in a wall of flue 25. The opening 42 is normally closed with a cover like cover 41, but is shown as having been removed. The openings 40 and 42 are opposite the respective regenerators 19 and 15. As shown, a long pipe 44 may be inserted through opening 42 so as to direct a stream of gas into the flues beneath the checker work 15. The pipe also may be positioned to direct gas down toward the bottom of flue 25. The pipe or lance 44 is connected through a hose 46 to a source of oxygen or oxygen rich gas.

When it is desired to clean out the flues, the

lance 44 is inserted and the gas is turned on by opening valve 45 so that a stream of oxygen rich gas is directed into the flue and against the dust deposit thereon. With the dust at an elevated temperature, the stream of gas causes the dust to glow and as a result of oxidation of part of the dust constituents, the dust deteriorates into a residue of fine particles and gases. The draft through the flue carries the residue out the stack and the deposits in these flues are relatively quickly and thoroughly removed in this manner. Preferably, the draft is left on while the dust is being removed so that gas is flowing from the hearth through the flues and to the stack. This gas will carry out the residue to the stack. After the dust has been removed the lance 44 is removed and opening 42 is closed. The pipe 44 can be inserted through opening 40 to remove the dust from the flues at the opposite end of the furnace.

In order for the dust to be at least partially oxidized by means of a stream of oxygen or oxygen rich gas, the dust must be at an elevated temperature. The reaction temperature of the dust depends upon the degree of oxygen purity of the gas and the degree of oxygen purity of the gas in turn depends in part on the temperature of the dust. When the dust is at a temperature of 1000° F. the gas directed against the dust deposit must contain at least 90% by volume of gaseous oxygen. When the dust is at a higher temperature of at least 1400° F., the gas may be one that is predominately free oxygen gas, that is, the gas must contain at least 50% by volume of free oxygen. Normally the gas other than oxygen present in the stream impinging against the dust will be nitrogen. Other relatively inert gases which do not burn or combine with the oxygen under the conditions existing may be present. Where impure oxygen is used, the impure oxygen may be obtained, for example, by mixing air and relatively pure oxygen.

Referring more particularly to Figure 3, the means for cleaning the flues may be permanently mounted in the furnace flue. A distributor pipe 47 is mounted on and extends through the wall of flue 27 and has connected thereto tubes or nozzles 48 arranged to direct streams of gas into flues 21. The distributor pipe 47 contains a valve 49 and is connected to a source of oxygen or oxygen rich gas through pipe 50. Tubes 51 extend from pipe 47 into flue 27 for directing gas against the dust on the bottom of flue 27. In operation, the valve 49 is open and oxygen or oxygen rich gas is directed from nozzles 48 and 51 against the dust in flues 21 and 27 to remove the dust as previously described.

As pointed out previously, preferably gas is flowed through the flues to the stack 26 to carry out the residue resulting from the at least partial oxidation of the dust. When fuel is being burned in chamber 11 while the dust is being removed, then the gas flowing through the flue is gaseous products of combustion. If no fuel is being burned then the gas may be air that is blown through chamber 11, then through the regenerator and through the flues being cleaned to the stack.

The present invention has been described in detail in connection with an open hearth furnace but is not limited to such a furnace. Its principles may be utilized for removing dust which is at least partially oxidizable, and which has dropped out of other combustion gases. Dust

may be removed, as described, from passages leading to, through or from other regenerators or checkerwork, for example, the flues of coke plants.

5 I claim:

1. The method of removing dust from a passage comprising flowing gaseous products of combustion through and then out of a passage in one direction, the gaseous products of combustion carrying dust particles that collect in the passage, impinging a stream of gas containing at least 90% by volume of free gaseous oxygen against the collected dust in the passage while the dust is at a temperature of at least 1000° F. and thereby effecting oxidation of at least part of the dust, and flowing the dust residue out of the passage in the same direction as the gaseous products of combustion.
2. The method of removing dust from a passage comprising flowing gaseous products of combustion through and out of a passage in one direction, the gaseous products of combustion carrying dust particles that collect in the passage, impinging a stream of gas containing at least 50% by volume of free gaseous oxygen against the collected dust in the passage while the dust is at a temperature of at least 1400° F. and thereby effecting oxidation of at least a portion of the dust, and flowing the dust residue out of the passage in the same direction as the gaseous products of combustion.
3. In the method of cleaning a passage to remove a dust deposited in the passage from dust laden gaseous products of combustion flowing through the passage, the steps comprising impinging a stream of gas containing at least 90% by volume of free gaseous oxygen against the dust deposit while the dust is at a temperature of at least 1000° F., and thereby effecting oxidation of at least a portion of the dust, and simultaneously flowing other gas through the passage to carry the dust residue out of the passage.
4. In the method of cleaning a passage to remove a dust deposited in the passage from dust laden gaseous products of combustion flowing through the passage, the steps comprising impinging a stream of gas containing at least 50% by volume of free gaseous oxygen against the dust deposit while the dust is at a temperature of at least 1400° F., and thereby effecting oxidation of at least a portion of the dust, and simultaneously flowing other gas through the passage to carry the dust residue out of the passage.
5. In the method of removing dust from a passage communicating with a regenerator, the steps comprising alternately, countercurrently passing relatively hot gaseous products of combustion and relatively cool gas through such a passage and regenerator so that the regenerator is alternately heated by the hot gaseous products of combustion and cooled by the cool gas, the hot gaseous products carrying dust particles that collect in the passage, and directing a stream of gas containing at least 90% by volume of oxygen against the collected dust in the passage while the dust is at a temperature of at least 1000° F. and thereby effecting oxidation of at least part of the dust, and simultaneously passing gas through the passage in the same direction as the hot gaseous products of combustion to carry the dust residue out of the passage.
6. In the method of removing dust from a

passage communicating with a regenerator, the steps comprising alternately, countercurrently passing relatively hot gaseous products of combustion and relatively cool gas through such a passage and regenerator so that the regenerator is alternately heated by the hot gaseous products of combustion and cooled by the cool gas, the hot gaseous products carrying the dust particles that collect in the passage, and directing a stream of gas containing at least 50% by volume of oxygen against the collected dust in the passage while the dust is at a temperature of at least 1400° F. and thereby effecting oxidation of at least part of the dust, and simultaneously passing gas through the passage in the same direction as the hot gaseous products of combustion to carry the dust residue out of the passage.

7. The method of operating an open hearth furnace comprising passing hot gaseous products of combustion from the hearth of an open hearth furnace through a regenerator of refractory brickwork and then through a flue passage and to a stack and alternately countercurrently passing cool air through the flue passage and then through the regenerator to the furnace hearth, the hot gaseous products of combustion carrying dust from the hearth and at least part of the dust being deposited in the regenerator and flue passage, periodically removing the dust deposited in the flue passage by directing a stream of gas containing at least 90% by volume of gaseous oxygen against the dust while at a temperature of at least 1000° F. and thereby effecting oxidation of at least part of the dust, 35

and simultaneously passing gas through the regenerator and then through the flue passage to the stack to carry out the residue.

5 8. The method of operating an open hearth furnace comprising passing hot gaseous products of combustion from the hearth of an open hearth furnace through a regenerator of refractory brickwork and then through a flue passage and to a stack and alternately countercurrently 10 passing cool air through the flue passage and then through the regenerator to the furnace hearth, the hot gaseous products of combustion carrying dust from the open hearth furnace and at least part of the dust being deposited in the regenerator and flue passage, periodically removing the dust deposited in the flue passage by applying a stream of gas containing at least 50% by volume of gaseous oxygen against the dust while at a temperature of at least 1400° F. and thereby effecting oxidation of at least part of the dust, and simultaneously passing gas through the regenerator and then through the flue passage to the stack to carry out the residue.
